UNITED STATES PATENT OFFICE.

CHARLES P. MOSHER, OF PHILADELPHIA, PENNSYLVANIA.

CHERRY-STONER.

SPECIFICATION forming part of Letters Patent No. 690,983, dated January 14, 1902.

Application filed August 3, 1901. Serial No. 70,746. (No model.)

To all whom it may concern:

Be it known that I, CHARLES P. MOSHER, a citizen of the United States, residing in the city and county of Philadelphia, State of Pennsylvania, have invented a new and useful Improvement in Cherry-Stoners, of which the following is a specification.

My invention consists of an improvement in cherry-stoners having adjustable jaws and having means connected with one of said jaws for operating both of said jaws.

It further consists of novel details of construction, all as will be hereinafter set forth.

Figure 1 represents a side elevation of a portion of a cherry-stoner embodying my invention. Figs. 2 and 3 represent bottom plan views of a portion of the device on an enlarged scale, showing different means for connecting the jaws. Fig. 4 represents a sectional view 20 on line $\alpha\alpha$, Fig. 2.

Similar letters of reference indicate corresponding parts in the figures.

Referring to the drawings, A designates a cherry-stoner having a standard or support 25 B, the hopper C, and the wheel D, suitably journaled in said hopper in the opening E, which is in the spout F of said hopper, said wheel being operated by the handle G, secured thereto.

30 H and J designate jaws, which are pivoted to a suitable portion of the stoner—in the present case at K and L, respectively—and are provided with the lugs or extensions M and N, respectively, which are pivoted together by the pin P, said jaws having the sides Q in the opening E.

R designates a thumb-screw having the shoulders S thereon, forming the neck T, which is adapted to fit between the ears U 40 on one of the jaws—in the present case on the jaw H—and said screw engaging with the stationary lug V on the spout F of the hopper C.

A' designates lugs or shoulders on the hopper, on which the ends of the jaws H and J 45 are adapted to rest and move, whereby the same are properly supported.

The operation is as follows: The cherries to be stoned are placed in the hopper and the wheel turned, whereby the stones or pits are 50 removed from the cherries, which latter pass out of the spout F into a suitable receptacle.

Owing to the different sizes of the cherries which it may be necessary to stone, it is essential in machines of this character that provision be made therefor, and I can accomplish this by reason of the adjustability of the jaws H and J, which latter can be moved in or out, thus increasing or decreasing the space between the sides Q and the wheel D, it being seen that by the manipulation of the screw R both of the said jaws H and J are simultaneously opened or closed and are held in their adjusted position, whereby it will be seen that the said jaws can be quickly and easily adjusted, even during the operation of the machine, and when so adjusted remain in the position until moved therefrom by again manipulating the screw R.

In Fig. 3 I have shown a construction similar to that already described, excepting that 70 on the face of the lugs M and N, I place teeth, which mesh with each other, whereby by operating the screw the jaws are simultaneously adjusted.

On the periphery of the wheel D, I provide 75 projections B', which are adapted to prevent the cherries from sticking in the opening E.

It will be evident that various changes may be made by those skilled in the art which will come within the scope of my invention, and 80 I do not, therefore, desire to be limited in every instance to the exact construction herein shown and described.

Having thus described my invention, what I believe to be new, and desire to secure by 85 Letters Patent, is—

1. In a cherry-stoner, jaws mounted thereon and means for simultaneously adjusting said jaws and holding said jaws in adjusted position, whereby the device is adapted to 90 stone different-sized cherries.

2. In a cherry-stoner, jaws mounted thereon, and means for connecting said jaws whereby the same are simultaneously adjusted and held in adjusted position.

3. In a cherry-stoner, a spout thereon, a wheel mounted in said spout, jaws pivoted thereto, lugs thereon, a pin connecting said jaws and means connected with one of said jaws for operating both jaws.

4. In a cherry-stoner, jaws pivoted thereon, lugs thereon, a pin connecting said jaws,

means for operating said jaws, a wheel suitably journaled and projections on the periphery of said wheel.

5. In a cherry-stoner, a wheel suitably journaled, a spout, jaws therefor, and means for simultaneously adjusting said jaws and holding the same in adjusted position.

6. In a cherry-stoner, a wheel suitably journaled, a spout, jaws pivoted thereto, means

connecting said jaws, a lug on said spout and a screw engaging with one of said jaws and with said lug and adapted to be operated to adjust said jaws.

CHARLES P. MOSHER.
